UNITED STATES PATENT OFFICE

JAMES H. RAND, OF NORTH TONAWANDA, NEW YORK, ASSIGNOR TO REMINGTON RAND INC., OF NEW YORK, N. Y., A CORPORATION OF DELAWARE

INDEX DEVICE

Application filed June 11, 1924. Serial No. 719,306.

This invention relates to card units for card index systems and consists primarily in securing a cover or sheath of transparent sheet material to a card in such a manner that the 5 sheath may expand or contract without buckling the card. This and other features will be hereinafter more fully described and pointed out in the appended claims, and one embodiment of the invention is illustrated in 10 the accompanying drawings, in which

Fig. 1 is a front view of a holder and sheath;

Fig. 2 is a rear view; and

Fig. 3 is an enlarged section on the line 3—3 15 of Fig. 2.

The sheath which encloses one margin of the index card holder is ordinarily made of transparent sheet celluloid which heretofore has been secured to holders or index cards at 20 several points by staples or other means so that accidental separation of the cards or holders from the sheath incidental to their manipulation is prevented. The sheath however contracts and expands in response to 25 changes in temperature and humidity and as a result the card or holder to which it is secured buckles or becomes distorted.

The improved card holder illustrated comprises a sheet 1 of card board, paper or other 30 suitable material having strips 2 and 3 adjacent each side thereof permanently fixed to the opposite ends of sheath 4 which is preferably formed of transparent celluloid folded to form front and rear walls 5 and 6 defining 35 a pocket therebetween, the free edge of the front wall being bent inwardly to form a lip 7. The strips 2 and 3 are fixed to the sheath in such manner as to prevent a pivotal or turning movement therebetween as in 40 constructions similar to that disclosed in the patent to Rand No. 1,302,848 in which wire fasteners are employed. By the term "fixed" as above employed and as used in certain of the claims the applicant refers to a non-rotary or non-pivotal connection between the strip and the sheath. The front and rear wall of the sheath may be of the same width, as shown in Fig. 3. This involves a saving 45 of material over sheaths heretofore in use in 50 which the rear wall was wider than the front

wall to provide a portion to which staples could be conveniently attached. The sheet body 1 preferably though not necessarily extends to the line connecting the lower ends of strips 2, in which case the strips may be 55 formed merely by slitting the lower margin of the sheet as illustrated, and the margin 9 of the sheet extends into the pocket sheath.

When the strips 2 and 3 are formed by slitting the body sheet as aforesaid, they are 60 preferably connected to the outside of the sheath 4 so that they lie in a plane different from that of the central portion 9, whereby the inner edges of the strips do not engage the end edges of central portion 9 when the 65 sheath contracts.

Heretofore staples have been employed to secure a sheath to a sheet but they have been found disadvantageous because they catch in adjacent cards and the holes provided for the 70 staples weaken the margins of the sheet so that when the sheets are of ordinary paper the staples are frequently torn out of the holes. By fastening the sheath to the card by means of the strips 2 and 3 the above difficulties are overcome because the sheet is in no manner weakened by the connection, although the dimensions of the sheath can vary 75 without buckling the sheet 1.

As above pointed out the sheath 4 is connected to the sheet 1 only at the ends so that the intermediate portion of the sheath is unattached and pockets are thereby formed on both sides of the sheet 1. Index cards (not shown) may be inserted in the pockets formed between the walls of the sheath 4 and the sheet 1 on both sides of the sheet and bear suitable indicia according to the subject matter of the index. The index card on one side may be held to the sheet 1 by inserting 80 the upper corners thereof into slits 8 adjacent the top of the sheet.

I claim:

1. A holder for index slips comprising a sheet body and pocket sheath attached together by a narrow strip at each end of the sheath, said strips being integral with said body, and the ends of the strips attached to the sheath being free to move relative to the sheet body in a direction longitudinal to the 95 sheet body.

sheath to allow for expansion or contraction of the sheath.

2. A holder for index slips comprising a sheet having a sheath of transparent sheet celluloid enclosing one margin thereof, said sheath having front and rear walls united along one longitudinal edge, strips on said sheet formed by cutting slits adjacent opposed edges adapted to be secured to the outer side of the rear wall of the sheath to enable the celluloid to expand or contract without buckling the sheet, the intermediate portion of the sheath being unattached to provide pockets on both sides of the sheet to receive index slips.
3. A holder for index slips comprising a sheet body and a folded sheath fitting over one margin of the body, the body being slit at each end to form integral strips, and said strips being secured to the outside of the sheath.
4. A holder for index slips, comprising a card, a sheath engaging one margin of the card, and strips at opposite ends of the card extending laterally to the sheath, each strip having a corresponding end permanently fixed to the card and the opposite end secured to the sheath in offset relation to the card, said strips compensating for differences in expansion between the sheath and card.
5. A holder for index slips, comprising a card, a sheath engaging one margin of the card, and strips arranged in spaced relation, each having one end permanently fixed to the card and the opposite end permanently fixed to the sheath, said strips being provided to compensate for differences in expansion and contraction between the sheath and card.

Signed by me at Boston, Massachusetts,
this sixteenth day of May, 1924.

JAMES H. RAND.
